UNITED STATES PATENT OFFICE.

LOUIS G. PARENT, OF WINFIELD, NEW YORK, ASSIGNOR TO PARENT ELECTRIC COMPANY, INC., OF NEW YORK, N. Y., A CORPORATION OF NEW YORK.

ELECTRICAL CONNECTING DEVICE.

Application filed March 20, 1923. Serial No. 626,284.

To all whom it may concern:

Be it known that I, LOUIS G. PARENT, a citizen of the United States, residing at Winfield, in the county of Queens, State of New York, have invented certain new and useful Improvements in Electrical Connecting Devices; and I do hereby declare the following to be a full, clear, and exact description of the invention, such as will enable others skilled in the art to which it appertains to make and use the same.

This invention relates, in general, to electrical connecting devices, and, more particularly, spring jacks.

Radio receiving instruments, especially those of the less expensive variety, are not ordinarily provided with spring jacks for connecting in the telephones, but are, on the contrary, usually provided with binding posts for that purpose. When it is desired to connect in more than one pair of telephones, binding posts do not provide a convenient means for so doing. This is particularly true in cases where it is frequently desirable to alternately connect in one or a plurality of telephone sets without a considerable loss of time in effecting the changeover.

The present invention has for its object, therefore, to provide a device whereby the number of telephone headsets connected to a radio receiving instrument may be quickly and conveniently changed.

A further object is to provide a device of the character referred to which is adapted to be easily connected to variously spaced fixed terminals or binding posts on the receiving instrument.

According to the preferred embodiment of the invention, there is provided a portable multiple spring jack into which a plurality of plugs may be inserted having adjustable connecting means whereby the device may be readily connected with variously spaced binding posts. The jack springs are preferably so arranged and interconnected that when a plurality of telephone sets are connected in by means of suitable plugs, they are in series relation, but if conditions are such that parallel connections are desired, the jack springs can be easily arranged accordingly without departing from the spirit of the invention. The adjustable connecting means above referred to consists preferably of a pair of relative-

ly rigid L-shaped metal stampings each having a slot in one leg extending parallel to its length for facilitating lateral adjustments of the spacing between the other legs of the metal stampings—the last mentioned legs being arranged for connection to the binding posts. Suitable clamping screws and nuts are provided for securing the metal stampings in any position to which they may be adjusted. By assembling the metal stampings one way, connections may be made with very closely spaced fixed terminals, and by assembling them another way, connections may be made with quite widely spaced terminals. Thus it will be seen the invention provides for making connections with arbitrarily spaced terminals on the receiving instrument by means of connectors having sufficient stiffness to rigidly support the device.

The device may be designed to include as many jacks as desired within reasonable limits. The specific devices hereinafter described each includes only two jacks, but it will be readily seen that similar devices including three or more jacks may be provided with equal facility.

In the accompanying drawing and following detailed description two alternative embodiments of the invention are illustrated and described.

Referring to the drawings,

Fig. 1 is an elevational view, partly in cross section, of a connecting device in accordance with this invention, a portion of the jack supporting element having been removed for the sake of clearness;

Fig. 2 is an inside elevational view of that portion of the jack supporting element which is not shown in Fig. 1;

Fig. 3 is an elevational view similar to Fig. 1 and differs therefrom only in that the metal stampings forming the connecting media between the jacks and the fixed terminals on the receiving instrument are shown assembled in reverse arrangement as compared with the arrangement of Fig. 1;

Fig. 4 is a cross sectional view taken along the line 4—4 of Fig. 3;

Fig. 5 is a cross sectional view similar to Fig. 4 but showing a plug in dotted lines inserted in one of the jacks;

Figs. 6 and 7 are perspective views of jack springs embodied in the structures illustrated in the other figures;

Fig. 8 is an elevational view of an alternative embodiment of the invention, a portion of the supporting element having been removed in order to more clearly illustrate the structure;

Fig. 9 is an inside elevational view of that portion of the supporting element which is not shown in Fig. 8;

Fig. 10 is a cross sectional view along the line 10—10 of Fig. 8; and

Fig. 11 is an end view as observed from the top of Fig. 8.

The preferred embodiment of the invention illustrated in Figs. 1 to 5 inclusive comprises a member 1 which, for convenience, is referred to as a supporting element or housing member. The supporting element 1 is divided into two portions designated respectively 1^a and 1^b. These are preferably made of suitably molded dielectric material such as hard rubber or a phenolic condensation product. The portions 1^a and 1^b when fitted together, as is best illustrated in Figs. 4 and 5, define chambers or recesses enclosing jack springs 2 and 3. Jack spring 2, which is shown in perspective in Fig. 7, is U-shaped, and is secured to the portion 1^a of the supporting element by means of a screw 4. Jack springs 3 are likewise secured to the portion 1^a by means of the clamping screw 5. The free end portions 2^a and 2^b of jack spring 2 normally engage their respectively associated jack springs 3. The supporting element 1 is provided with a pair of apertures 1^c of suitable size for guiding the connecting plugs into engagement with the jack springs, as shown in Fig. 5.

In order to facilitate connecting this device with arbitrarily spaced binding posts, the spacing of which may vary considerably, a pair of L-shaped stamped metal conducting members 6 are provided. One leg of each of these conducting members is provided with a slot 6^a through which the clamping screw 5 extends. Each clamping screw is provided with a wing nut 7 and preferably with a pair of washers 8. By loosening the wing nuts 7 the conducting members 6 may be moved toward or away from each other, thus varying the distance between their free ends, which, in the present instance, are bifurcated for facilitating connections with the binding posts. When the conducting members are arranged as shown in Fig. 1, their free ends cannot be separated by any considerable amount, as will be clear from a consideration of the drawing, but they can be moved very closely together. These members may be turned about as shown in Fig. 3, in which position they are adapted to be connected with binding posts quite widely spaced. While the spacing between the free ends of the conducting members 6 is not particularly large, as illustrated in Fig. 3, it will be under-

stood that this may be increased to any desired extent by increasing the length of the slotted leg of one or both conducting members.

Since the jack springs are normally in contact and connected in series, the insertion of a plug into either jack connects it across the terminals to which the device is connected. The insertion of an additional plug in the other jack connects the two plugs in series. In other words, if two telephone headsets are connected to the device through the medium of their respective plugs, they are connected in series across the terminals of the receiving instrument. Since the best results are usually obtained in radio reception by connecting the telephones in series rather than in parallel, the jack springs have been so arranged in the present instance. It is, however, an easy matter to rearrange the contact springs for parallel connections, as will be readily understood by those skilled in the art.

The alternative structure illustrated in Figs. 8 to 11 inclusive differs from the preferred embodiment in only in the substitution of a simplified conducting member 9 for the L-shaped conducting member 6 of the preferred embodiment. The conducting member 9, instead of being provided with a slotted leg for lateral adjustments, is simply pivoted on the clamping screw 5, and is adapted to be swung into any one of a plurality of positions, as indicated by the dotted line showing in Fig. 8. The wing nut 7 is eliminated in the alternative structure, and clamping of the conducting members 9 in any position into which they may be set may be effected by turning clamping screw 5 with a screw driver. A plain nut 10 is provided for engaging screw 5 in place of the wing nut 7. The portion 11^b of the supporting element or housing member differs slightly from the portion 1^b of the supporting element 1 in that it is extended so as to match with the contour of the portion 11^a.

The invention is capable of great modification, and should not be construed as limited except by the scope of the appended claims.

I claim:

1. A portable jack-strip comprising a plurality of spring jacks, a housing member in which said jacks are mounted, a pair of rigid terminal connectors secured to said housing member and projecting therefrom, the free ends of said connectors being adapted for connection to binding posts and adjustable toward and away from each other so that connections can be made to variously spaced binding posts, said connectors being operative to support said housing member and jacks.

2. An electrical connecting device comprising a plurality of spring jacks combined with a common portable supporting ele-

- ment, and means for connecting said device to fixed terminals, said means comprising at least one rigid conducting member having a slot for permitting lateral adjustment, and means for securing said rigid conducting member in any one of a plurality of positions, said rigid conducting member being adapted for connection to a fixed terminal.
3. The combination with a portable jack strip including a plurality of spring jacks, of means for connecting the said jacks to variously spaced fixed terminals, said means comprising a pair of L-shaped relatively rigid conducting members, one leg of each of said members being slotted parallel to its length, clamping means engaging said members through the medium of said slots, said clamping means being operable to permit lateral adjustment of said members and for securing said members in any of a plurality of positions.
4. An electrical connecting device comprising a portable supporting element, a pair of spring jacks mounted adjacently on said supporting element, said jacks, jointly, comprising a U-shaped contact spring member which is secured at its middle portion to said supporting element, each of the free end portions of said U-shaped contact spring member being individual to one of said jacks, a second contact spring for each of said jacks normally in contact with their respectively associated free ends of the said U-shaped contact spring member, a pair of adjustable relatively rigid conducting members for connecting said jacks to fixed terminals and clamping means for securing said conducting members in any of a plurality of positions. In testimony whereof I affix my signature.

LOUIS G. PACENT.
